RUFFLER OPERATING MECHANISM

Victor J. Sigoda, Great Neck, N. Y., assignor to
Man-Sew Pinking Attachment Corp., New
York, N. Y., a corporation of New York

Application February 12, 1941, Serial No. 378,509

8 Claims. (Cl. 112—134)

This invention relates to ruffler operating mechanism and more particularly to certain improvements in ruffling attachments for sewing machines of the character shown and described in my pending application for Patent Ser. No. 310,844, filed December 23, 1939, now Patent No. 2,245,877, June 17, 1941, whereby the oscillatory ruffling blade may be actuated at any one of a plurality of selective speeds.

As disclosed in said pending application, the ruffling attachment embodying the oscillatory ruffling blade with the actuating mechanism therefor is operatively mounted in a housing attached to one end of the sewing machine arm, and said actuating mechanism operatively connected with the vertically vibrating needle bar of the machine. Broadly, the present invention resides in the substitution for this operating connection with the needle bar of a power transmitting mechanism operatively mounted at the other end of the sewing machine arm and including means whereby oscillatory motion is transmitted to the ruffling blade from the main shaft of the machine at a selected speed ratio.

It is another object of the invention to provide an improved mounting and arrangement of the variable speed operating mechanism for the ruffling blade upon the sewing machine arm so that there will be no interference with the conventional motor drive connection with the main shaft of the sewing machine and in which the several elements of said operating mechanism are compactly mounted and arranged within a housing of comparatively small dimensions.

It is a further general object of the present invention to provide such a variable speed operating means for the oscillatory ruffling blade which is simple in construction, reliable in its functional operation, and will not materially add to the production cost of the ruffling attachment as disclosed in my pending application.

With the above and other objects in view, the invention consists in the improved ruffler operating mechanism, and in the form, construction and relative arrangement of its several parts as will hereinafter be more fully described, illustrated in the accompanying drawings and subsequently incorporated in the subjoined claims.

In the drawings wherein I have shown one simple and practical embodiment of the invention, and in which similar reference characters designate corresponding parts throughout the several views:

Fig. 1 is a top plan view of a sewing machine

of standard make showing a preferred embodiment of my present invention applied thereto.

Fig. 2 is an end elevation, the face plate of the housing for the ruffler actuating mechanism being removed.

Fig. 3 is an elevation of the opposite end of the sewing machine with the face plate for the housing of the variable speed operating mechanism removed, and

10 Fig. 4 is a horizontal sectional view taken substantially on the line 4—4 of Fig. 3.

Referring in detail to the drawings, the conventional horizontally disposed sewing machine arm is indicated at 5, said arm being integrally connected at one end with the usual hollow standard or pedestal formed upon the base plate 6. The other end of this arm is provided with the usual guide head 7 for the vertically vibrating needle bar 8 and the presser foot bar 9. The 15 main shaft 10 is suitably mounted within the arm 5 and driven by the belt wheel 11, connected with the operating motor (not shown). The other end of the main shaft, is operatively connected with the needle bar 8 in a known manner to 20 transmit vertical reciprocating or vibratory motion thereto.

For the purpose of this description, I have shown my present improvements as applied to a ruffler actuating attachment similar to that shown 30 in my pending application, but it will be understood as this description proceeds, that the novel features of the present invention are not necessarily limited to a ruffling attachment of this specific type. It will, therefore, suffice to state that 35 the actuating means for the ruffling blade 13 is mounted within a suitable housing 14 attached to the end face of the needle guide head 7 of the sewing machine arm and includes means for regulating the extent of throw of said blade.

40 This actuating mechanism for the ruffling blade, generally indicated at 15, is operatively connected with one end of a rock shaft 16 which extends parallel with the arm 5 at the rear side thereof and is mounted at one of its ends in a suitable bearing provided on the side wall of the housing 14. The ruffling blade 13 is mounted for yielding pivotal movement on the lower end of an oscillatable arm 17 fixed at its upper end to a shaft 18 supported in the lower end of the 45 housing 14 and with which the actuating mechanism 15 is operatively connected. It will, therefore, be understood that in the rocking motion of the shaft 16 the mechanism 15 transmits similar rocking motion to the shaft 18 whereby the 50 arm 17 and blade 13 are oscillated so that said 55

Fig. 1 is a top plan view of a sewing machine

blade forms uniformly spaced ruffles in the fabric material as it is fed by the usual sewing machine feed mechanism beneath the presser foot 19 on the lower end of the presser foot bar 9.

At the other end of the sewing machine arm 5, the housing 20 is arranged, said housing having formed upon its rear side wall the attaching arm 21 suitably spaced from said side wall and adapted to be rigidly bolted or otherwise secured as at 22 to the supporting pedestal of the arm 5. The rear side wall of said housing is provided with the opening 23 to receive the hub extension 24 of the drive wheel 11 for the main shaft 10, and to the end of said shaft the gear 25 is suitably fixed, as by means of the screws 26 engaged in diametrically opposed openings of said gear and threaded into the hub 24. This gear is also provided with the opening 27 for a purpose which will be presently explained.

Upon a stud shaft 28 on the rear wall of the housing 20, the relatively large diameter gear 29 is rotatably mounted and in constant mesh with the gear 25. To one side of the gear 29 a smaller gear 30 is rigidly fixed by the screws 31 and is provided with an opening 32.

The gear 30 is in mesh with the relatively large gear 33 mounted on the stud shaft 34 on the wall of the housing 20, said latter gear being provided with the opening 35.

The other end of the rock shaft 16 extends through a suitable bearing on the arm 21 and the bearing boss or sleeve 36 formed on the wall of the housing 20. To the end of this shaft one end of a radially extending rod or arm 37 is rigidly fixed as by means of the set screw 38. A sleeve 39 is slidably adjustable along this rod and a pin 40 is movable in the laterally projecting lug 41 formed on the sleeve 39. This pin is threaded in the lug and has loose engagement in the gear openings 27, 32 and 35.

The open front side of the housing 20 is closed by a removable face plate 42 so that in the operation of said mechanism the several parts thereof are completely housed and protected against possible damage.

By means of the mechanism above described, it will be seen that the rapidity of oscillating motion of the rock shaft 16, and therefore of the ruffling blade 13, may be regulated and varied by adjustably connecting the rod or arm 37 fixed to one end of said rock shaft with the various gear elements of the power transmitting mechanism. Thus, when the pin 40 is engaged in the opening of the gear 33, the shaft 16 will be actuated at a 1 to 4 ratio with respect to the main drive shaft 10 of the sewing machine. By manually adjusting the position of the rod 37 and the sleeve 39 thereon to engage the pin 40 in the opening 32 of gear 30, the shaft 16 will then be actuated at a 1 to 2 ratio, and when said rod is again adjusted and the pin 40 thereon engaged in the opening 27 of the gear 25, the shaft 16 will be actuated at a 1 to 1 ratio with respect to the main drive shaft 10. In this manner, the oscillating motion of the ruffling blade 13 may be selectively controlled and its rate of throw governed to produce a desired predetermined number of ruffles per inch in the fabric as it is fed beneath the sewing machine presser foot to the needle carried by the needle bar 8. The above described adjustments of the operating connection between rod or arm 37 and the power transmission gears may be easily and quickly made merely by removing the face plate 42 of the gear housing 20. I have above referred to certain

ratios of operation of the rock shaft 16 with respect to the main drive shaft merely by way of illustration, but it will be seen that any other desired ratios may be provided merely by altering the relative diameters of the several transmission gear elements and properly locating the respective openings in said gear elements to receive the adjustable pin 40.

From the foregoing description considered in connection with the accompanying drawings, the construction, manner of operation and several advantages of the present invention will be clearly and fully understood. It will be seen that I have devised a very simple addition to the attachment shown in my pending application whereby the oscillatory movements of the ruffling blade may be selectively controlled so as to vary the spacing of the ruffles formed in the fabric material. It will further be apparent that the device, while of very simple construction, will be positive and reliable in its operation, and will not greatly increase the production cost of the original attachment. In the foregoing description and the accompanying drawings, I have illustrated a mechanical embodiment of my present improvements which after thorough test has been found highly satisfactory. Nevertheless, it is apparent that with respect to the detail mechanical parts and their relative mounting and arrangement in the housing 20, and also the construction and mounting of said housing on the sewing machine, the invention is susceptible to more or less modification and change. Accordingly, the privilege is reserved of embodying the essential features of the present disclosure in such other alternative structural forms as may fairly be considered as within the spirit and scope of the appended claims:

I claim:

1. In combination with a sewing machine having a main needle actuating shaft, ruffling mechanism mounted at one end of said shaft including an oscillatory ruffling blade and an operating shaft for said blade, a gear train driven from the opposite end of said needle actuating shaft and having gear elements of relatively different diameters, a member fixed to the ruffling blade operating shaft and means mounted on said member for radial adjustment with respect to the ruffling blade operating shaft and including a part adapted to be selectively engaged with means on the respective gear elements to actuate the latter shaft at a predetermined speed.

2. In combination with a sewing machine having a main needle actuating shaft operatively connected at one end with the sewing machine needle, ruffling mechanism mounted at said end of the needle actuating shaft including an oscillatory ruffling blade and operating means therefor embodying a rock shaft, and means operatively connecting the needle actuating shaft with said rock shaft comprising a plurality of power transmission elements driven from the needle actuating shaft at relatively different speeds; and means for selectively connecting said elements with said rock shaft to selectively transmit oscillating motion to said rock shaft at any one of a plurality of predetermined speeds.

3. In combination with a sewing machine having a main needle actuating shaft operatively connected at one end with the sewing machine needle, ruffling mechanism mounted at said end of the needle actuating shaft including an oscillatory ruffling blade and operating means therefor embodying a rock shaft, a gear train driven from

the other end of said needle actuating shaft and having gear elements of relatively different diameters, and power transmission means connected with said rock shaft and comprising a radially adjustable element having a part adapted to be selectively engaged with means on the respective gear elements to transmit oscillating motion to said rock shaft at a selected predetermined speed.

4. In combination with a sewing machine having a main needle actuating shaft operatively connected at one end with the sewing machine needle, ruffling mechanism mounted at said end of the needle actuating shaft including an oscillatory ruffer blade and operating means therefor embodying a rock shaft, a gear train driven from the other end of said needle actuating shaft and having gear elements of relatively different diameters, an arm fixed to the corresponding end of said rock shaft, and a member longitudinally slideable on said arm having means adapted to be selectively connected with said different gear elements to transmit oscillating motion to said rock shaft at a predetermined speed.

5. In combination with a sewing machine having a main needle actuating shaft, ruffling mechanism including an oscillatory ruffling blade and an operating shaft therefor, a plurality of power transmission elements operable at relatively different speeds and a driving connection between the same and said needle actuating shaft, and means for operatively connecting a selected individual power transmission element with the blade operating shaft to actuate the latter at a predetermined speed relative to the needle actuating shaft.

6. In combination with a sewing machine having a vertically reciprocating needle, an oscillatory ruffling blade mounted in operative relation to the sewing machine needle and actuating means therefor including a rock shaft, an operating means for said rock shaft comprising a plurality of power driven transmission elements operable at relatively different speeds, and means for selectively connecting the individual power transmission elements with said rock shaft to actuate the latter at a predetermined speed.

7. In combination with a sewing machine having a vertically reciprocating needle, an oscillatory ruffling blade mounted in operative relation to the sewing machine needle and actuating means therefor including a rock shaft, an operating means for said rock shaft comprising a plurality of power driven transmission elements operable at relatively different speeds, and means for selectively connecting the individual power transmission elements with said rock shaft to actuate the latter at a predetermined speed.

10 8. In combination with a sewing machine having a vertically reciprocating needle, an oscillatory ruffling blade mounted in operative relation to the sewing machine needle and actuating means therefor including a rock shaft, an operating means for said rock shaft comprising a plurality of power driven transmission elements operable at relatively different speeds, a member fixed to the rock shaft disposed radially thereof, and an element carried by said member, adjustable relative thereto and adapted to coact with means on a selected individual power transmission element to actuate the rock shaft at a predetermined speed.

15 9. In combination with a sewing machine having a vertically reciprocating needle, an oscillatory ruffling blade mounted in operative relation to the sewing machine needle and actuating means therefor including a rock shaft, an operating means for said rock shaft comprising a plurality of power driven transmission elements operable at relatively different speeds, a member fixed to the rock shaft disposed radially thereof, and an element carried by said member, adjustable relative thereto and adapted to coact with means on a selected individual power transmission element to actuate the rock shaft at a predetermined speed.

20 10. In combination with a sewing machine having a vertically reciprocating needle, an oscillatory ruffling blade mounted in operative relation to the sewing machine needle and actuating means therefor including a rock shaft, an operating means for said rock shaft comprising a plurality of power driven transmission elements operable at relatively different speeds, a member fixed to the rock shaft disposed radially thereof, and an element carried by said member, adjustable relative thereto and adapted to coact with means on a selected individual power transmission element to actuate the rock shaft at a predetermined speed.

25 11. In combination with a sewing machine having a vertically reciprocating needle, an oscillatory ruffling blade mounted in operative relation to the sewing machine needle and actuating means therefor including a rock shaft, an operating means for said rock shaft comprising a plurality of power driven transmission elements operable at relatively different speeds, a member fixed to the rock shaft disposed radially thereof, and an element carried by said member, adjustable relative thereto and adapted to coact with means on a selected individual power transmission element to actuate the rock shaft at a predetermined speed.

30 12. In combination with a sewing machine having a vertically reciprocating needle, an oscillatory ruffling blade mounted in operative relation to the sewing machine needle and actuating means therefor including a rock shaft, an operating means for said rock shaft comprising a plurality of power driven transmission elements operable at relatively different speeds, a member fixed to the rock shaft disposed radially thereof, and an element carried by said member, adjustable relative thereto and adapted to coact with means on a selected individual power transmission element to actuate the rock shaft at a predetermined speed.

35 13. In combination with a sewing machine having a vertically reciprocating needle, an oscillatory ruffling blade mounted in operative relation to the sewing machine needle and actuating means therefor including a rock shaft, an operating means for said rock shaft comprising a plurality of power driven transmission elements operable at relatively different speeds, a member fixed to the rock shaft disposed radially thereof, and an element carried by said member, adjustable relative thereto and adapted to coact with means on a selected individual power transmission element to actuate the rock shaft at a predetermined speed.

VICTOR J. SIGODA.
